UNITED STATES PATENT OFFICE

2,280,219

ATTACHMENT FOR TABULATING MACHINES

Allen B. Cooke, Danville, Ill., assignor to United Autographic Register Co., a corporation of Illinois

Original application March 29, 1940, Serial No. 326,737. Divided and this application January 30, 1941, Serial No. 376,681

10 Claims. (Cl. 197—133)

This invention relates to an attachment for a typewriting machine, such as a tabulating machine, to adapt it to the use of continuous-form stationery strips which may be drawn around the power driven rotatable platen roll.

The present application is a division of my application Serial No. 326,737, filed March 29, 1940, for an Attachment for a tabulating machine.

The primary object of the present invention is to provide an improved attachment wherein feeding-units, which may be in the form of endless belt conveyer members, may be readily moved to accommodate various lateral or longitudinal spacings of perforations in the stationery.

A further object of the invention is to provide an improved fixture, or cradle, on the attachment so that a feeding-unit may easily be slipped into a position where it is supported by the cradle member and may be locked in position by the driving-shaft which impales the feeding-unit.

Another object of the invention is to provide improved guide means for holding the stationery in engagement with the feeding units.

The attachment in the present invention is an improvement over the device shown in Jensen Patent No. 2,130,015, issued September 13, 1938.

The invention is illustrated in a preferred embodiment in the accompanying drawing, in which—

Figure 1 is a fragmentary vertical sectional view of a machine embodying the invention; and Figure 2, a plan view perpendicular to the base of the cradle member with the feeding-unit removed.

In the embodiment illustrated, A designates the main frame of the attachment; B, cradle members; and C, feeding-units which are adapted to be removably supported in the cradle members B.

In the embodiment illustrated the frame A has side plates 9 which are held in spaced relation by means of a pair of square cross bars 10 and a cross rod 11. The side plates are provided with slots 12 adapted to fit on to parts of a standard tabulating machine and be held in position by a spring clip (not shown).

A driving-shaft 13 is journaled in the side plates 9 and is adapted to impale feeding-units C which are held in the cradles B. The shaft 13 is withdrawable laterally to permit the feeding-units to be detached.

The cradle members B are skeleton channel-like members whose side walls are cut away to 55

form upper jaws 14 and lower jaws 15 which open downwardly so that they may receive the cross bars 10 of the frame. Bolts 16, with winged heads, are threaded to the base of the cradle members so that they may be screwed against the cross bars to hold the device in position thereon. The side walls have upward extensions 17 and 18 to embrace the side walls of the housing of the feeding-unit. The upper extension 18 is provided with a pair of open ended slots 19 extending upwardly and rearwardly to receive studs provided on the housing of the feeding-unit. The lower extensions 17 are provided with open ended slots 20 which extend upwardly and forwardly. It may be noted that the slots 20 are disposed at right angles to the slots 19, so that in attaching the feeding-unit, it is necessary to engage the studs in the slots 19 first. The cradle members are also provided with bracing cross bars 21 to make the structure more rigid.

The feeding-units C may be of any desired construction that can be driven by the shaft 13. In the embodiment illustrated each unit has a housing 22 provided with a pair of laterally extending studs 23 to engage slots 19 in the cradle member and a pair of lower laterally extending studs 24 to engage slots 20. Within the housing of the feeding-unit is journaled a lower sprocket wheel 25 which is adapted to be impaled by and make a driving connection with the shaft 13. An upper sprocket pulley 26 is journaled in the housing and an endless chain 27 is reefed around the two sprockets. The chain 27 is provided with a suitable number of feeding pins 28 which are adapted to engage spaced holes in continuous-form stationery 29 which is drawn from beneath the attachment, around a platen roll indicated at 30, into engagement with the feeding-units.

A rectangular guide frame is detachably secured to the side walls 9 of the attachment so that it may be snapped into position by means of spring latches 31. The frame has cross bars 32 and longitudinal standards 33. Longitudinally extending guide members 34 are secured to the cross bars 32 by lugs 35 and serve to hold the stationery in engagement with the feeding mechanism as the stationery advances. A bail-like guide member 36 makes a telescoping connection with a pair of supporting members 37 attached to the side frames 9. This guide is adjustable vertically for different lengths of feeding-units and serves to direct the stationery away from the attachment after it is released by the feeding-units.

Frequently, in using a machine of this charac-

ter, it is desirable to change from stationery of one width to stationery of another width. Obviously, the feeding-units have to be arranged in almost exact spaced relation on the cross bars 10 in order that the pins will engage the perforations. By using a plurality of cradle members, the cradle members may be very carefully adjusted in proper spaced relation, so that when the feeding-units are installed, they will be in proper position to take care of the lateral spacing of the holes. On the other hand, it is sometimes desirable to change from strips of one form length to strips of another form length. Where only one set of perforations is provided in each form length, it will be understood that different feeding-units C must be installed wherein the pins on the feed belts are spaced to accommodate a particular form length. By using the cradle members this change can be made just as easily and one feeding-unit may be taken out and another replaced by merely withdrawing the drive-shaft 13, lifting the lower end of the housing to disengage the studs 24 from the slots 20 and lifting the feeding-unit upwardly. The substituted feeding-unit may be installed by reversing the procedure.

The foregoing detailed description has been given for clearness of understanding only, and no unnecessary limitations should be understood therefrom for some modifications will be obvious to those skilled in the art.

I claim:

1. A typewriter attachment having fixed cross-bars and a drive-shaft, a cradle member mounted on said cross-bars and means on said cradle member for supporting a feeding-unit, said cradle member comprising a channel-like member having spaced apart jaws adapted to receive the fixed cross-bars, means for securing said jaws to the cross-bars in a desired position along the lengths of the cross-bars, and slots in the cradle to receive studs on the feeding-unit whereby the feeding-unit may be detachably held in said cradle, said drive-shaft being positionable to effect operative engagement with the feeding-unit.

2. A device as specified in claim 1, in which the jaws of the cradle member open downwardly, and the securing means comprises winged bolts making threaded engagement with the lower portion of the jaws and projecting against the lower side of a fixed cross bar.

3. A typewriter attachment having fixed cross-bars and a drive-shaft, a cradle member having spaced apart jaws adapted to receive and engage said cross-bars at a desired position along the lengths of the cross-bars, said cradle member also having upwardly extending slots, and a feeding-unit having a housing containing a driving sprocket for stationery feeding means, said housing having outwardly extending fixed studs adapted to fit into the slots of the cradle and be

held thereby with the sprocket in operative engagement with the feed-shaft.

4. In a device of the character set forth, a cradle member comprising: a channel-like member having a base portion and integral side walls cut away to form notches adapted to receive cross bars on which the member may be supported, said side walls having extensions to embrace a housing of a feeding-unit, the extensions having an upper pair of open ended slots and a lower pair of open ended slots, said slots being adapted for engagement with laterally extending studs on the housing of a feeding-unit.

5. A device as specified in claim 4, in which the upper pair of slots is disposed at substantially right angles to the lower pair of slots so that in attaching a feeding-unit one pair of slots must be fully engaged before the others can be brought into engagement with the studs.

6. In a typewriter attachment having fixed cross bars and an axially withdrawable drive-shaft, a cradle mounted on the fixed bars of the attachment, and a feeding-unit adapted to fit into said cradle and be impaled by the drive-shaft of the attachment to effect operative engagement therewith.

7. A device as specified in claim 6, in which the feeding-unit makes a pin-and-slot connection with the cradle and is releasably locked in the cradle by the withdrawable drive-shaft.

8. A typewriter attachment having fixed cross bars and a withdrawable driving-shaft, a cradle member secured to said cross bars, and a feeding-unit adapted to fit into said cradle and be impaled by the driving-shaft, said shaft serving to lock said feeding-unit to the cradle.

9. A continuous-form stationery attachment for a tabulating machine having a power driven platen roll, comprising: a frame having a pair of transverse bars, a plurality of cradle members mounted for adjustment longitudinally of said bars, each of said cradle members being a channel-like member having a pair of upwardly and rearwardly extending slots at its upper end and a pair of upwardly and forwardly extending slots at its lower end; a feeding-unit having a housing in which is journalled a pair of sprocket wheels encircled by an endless chain, said housing having pairs of upper and lower outwardly extending studs adapted to fit into the slots of a cradle member; and an axially withdrawable drive-shaft journalled in said frame and adapted to impale and make a driving connection with the lower sprocket wheel of the feeding-unit when in the cradle.

10. A device as specified in claim 9, including a removable front guide frame to direct stationery against feed pins provided on the conveyer chain.
